UNITED STATES PATENT OFFICE.

ALFRED B. WALES, OF WHITMAN, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

BUTTONHOLE SPACER AND MARKER FOR BUTTONHOLE-MACHINES.

1,134,966.

Specification of Letters Patent.

Patented Apr. 6, 1915.

Application filed March 5, 1910. Serial No. 547,460.

To all whom it may concern:

Be it known that I, ALFRED B. WALES, a citizen of the United States, residing at Whitman, in the county of Plymouth and State of Massachusetts, have invented an Improvement in Buttonhole Spacers and Markers for Buttonhole-Machines, of which the following description, in connection with the accompanying drawings, is a specification, like letters on the drawings representing like parts.

This invention relates to the spacing of button-holes and particularly to a button-hole spacer and marker for a button-hole machine.

The cutting and stitching or sewing of button-holes, and especially such a formation of button-holes in such work as shoes, requires an accurate spacing of each hole with regard to the hole last made. It is, moreover, desirable that such spacing be marked so as to be visible to the operator of the machine, while preferably such mark should not be of such permanent nature as to deface the work. It is, furthermore, desired that such a spacer and marker be applicable to any button-hole machine without reorganization of the machine or the attachment, or of the cutting and sewing or stitching mechanisms or devices.

To the end, therefore, of providing a spacing and marking mechanism which shall be capable of performing these desired functions and at the same time have the necessary characteristics of adaptability to various machines, I have devised my present invention, which, broadly stated, comprises the combination with a buttonhole making machine, including buttonhole cutting mechanism and buttonhole stitching mechanism, of means automatically operated once only during each complete cycle of operations of the machine to mark the work for the next succeeding buttonhole at a predetermined distance from the buttonhole being made so that the mark thus produced may be utilized in locating the work accurately for the making of such next succeeding buttonhole.

In the specific embodiment of the invention about to be described, I have provided for the adjustment of a marker with relation to the point of operation of the machine and for the gaging of such adjust-

ment with regard to the scales necessary for different sorts of work, and furthermore for the application of such a device to any properly timed and located part of the machine upon which it is to be used.

My invention comprises a point-like device combined with a movable part of the machine which will move said point downwardly into forcible marking engagement with the work invariably at the same distance from the preceding buttonhole once for each button-hole, so that when the work is moved along the mark thus made on the work will indicate the correct position for the next button-hole each time the work is moved.

The structure and operation of my device will be more fully described in the specification which follows and it is illustrated in the drawings which form a part of that specification. In these drawings I have shown as an illustrative embodiment of my invention a combined spacer and marker adapted to be attached to a button-hole machine of a standard type, and this embodiment I have described in the specification, reference being made to corresponding parts by the use of reference numerals similarly applied throughout.

In the drawings:—Figure 1 is a side view partly in section of the portion of a button-hole machine equipped with a spacer and marker, in accordance with my invention, Fig. 2 is an enlarged plan view of the same with the upper portion of the machine broken away, Fig. 3 is a detail in plan of the marker arm and adjusting lever, Fig. 4 is a sectional detail of the presser foot viewed from a direction opposite to that of Fig. 1, and Fig. 5 is a sectional detail on the line 5—5, Fig. 2.

1 is the overhanging head, 2 the bed and 3 the base of a button-hole machine.

4 is a needle carried, operated and guided in any usual manner.

5 is a button-hole cutter or knife carried on an arm 6 which is rocked and timed in any suitable manner to cut the button-holes which are to be stitched.

7 and 8 are a pair of oppositely faced presser feet.

As will be seen by reference to Figs. 1 and 4, the right hand arm 9 is pivoted at

10 between the ears of a block 11 which is screwed to the bed 2 of the machine. The lower end of the arm 9 is carried down and terminates in a return hook 9' which is engaged by an oppositely faced hook 11^x (see Fig. 1.) The hook 11^x is raised and lowered by a toggle 12 which is pivoted at its upper end 13 to the bed of the machine and at its lower end 14 to a bar 15 connected to the hook 11^x.

16 is a hand lever engaging at its lower end 16' the center pivot of the toggle 12. With the lever in the position shown in Fig. 1 the toggle 12 is in its collapsed position. By drawing the lever 16 toward the left of Fig. 1 the toggle 12 will be straightened and the hook 11^x depressed, thus rocking the arm 9 and depressing the presser foot.

20 17 is a work gage suitably mounted behind the operating point of the machine and suitably adjusted relative thereto.

20 is a plate having an extension 21 upon which a clamping strip 22 is held by the 25 screws 23. By adjusting the screws 23 the arm 9 of the presser foot 7 may be clamped between the extension 21 and the strip 22. This permits the adjustment of the spacer and marker of which the plate 20 is a part 30 upon the arm of the presser foot. On the under side of the plate 20, adjacent the part 22, is pivoted an arm 24 through the forward end of which is set a pointed screw 25. The point of the screw 25 constitutes a 35 marker which will make an impression on the surface of the leather, or other upper material, sufficient to be discernible. This impression, however, will subsequently disappear but will remain visible long enough 40 for the operator to use it in properly positioning the work under the knife and needle.

The arm 24 is continued beyond its pivot at 26 so that it is in the form of a bent lever or bell crank. On the end of the extension 26 is a segmental gear 27 with which meshes a pinion 28 formed on the end of a lever 29. The lever 29 is pivoted centrally of the plate 20 on a stud 30 upon the upper end of which is a thumb nut 31 which may 50 be loosened to move or replace a gage disk 32.

33, 34 and 35 are a plurality of scales of increasing size in graduation. These, for instance, would be respectively for children's, women's and men's size shoes.

The disk 32 is provided with perforations 36 of a number corresponding to that of the scales, that is in the present case there would be three perforations. These 60 perforations are adapted to be engaged by a pin 37 so that any one of the different scales which may be desired may be moved into the arc of play or field of the indicator or pointer 38 which is set on the lever 29 so as to overlap the margin of the plate 20

and travel with its point in close proximity to the margin of the disk 32 and of that scale which is located adjacent to its path.

The operation of my device is as follows: Supposing that the spacer and marker is 70 suitably mounted on the arm 9 with the point of the screw 25 adjusted so that when the presser foot 7 is raised it will be clear of the work beneath it but when the presser foot 7 is down it will be in marking contact 75 with the material of the upper, it will be evident that each time the presser foot is moved down into clamping position, the point of the screw 25 will be pressed hard against the top surface of the work so as to 80 make a preferably dull but clearly visible and well defined mark on the work. Inasmuch as this downward marking movement of the marker is caused automatically by a part, viz. the presser foot, which moves up 85 and down invariably in the same position with relation to the button-hole making mechanism, for instance with reference to the knife 5, it follows that the marker will accurately space the work, keeping just one 90 mark ahead of the actual button-holes all the time. As the work is moved into position to have a button-hole made in it, and is clamped by the presser foot, the marker 25 is thereby automatically brought down upon 95 the work in marking position, with the result that a mark is impressed on the work at a distance from the button-hole corresponding to the distance between the knife 5 and the screw 25. When the button-hole is finished and the work is moved along so as to bring the mark which has been thus made on the work into accurate position beneath the knife 5 and is then clamped, said clamping 100 movement causes the marker automatically 105 to make another mark at exactly the same distance from the point at which this second button-hole will be made that the first mark was made from the first button-hole. This marking is repeated, the spacing being always accurate and exactly the same, without any further attention from the operator, because the downward movement of the presser foot causes the marker each time to mark in its place, and as the presser foot has no lateral movement but always goes up and down in exactly the same path, it follows that the marker 25 necessarily marks invariably at 110 the same distance from the knife 5 and hence spaces the button-holes with the utmost accuracy. If a different spacing is desired, the arm 24 is swung to the right or left as required, by the manual adjusting means. The disk 32 should preliminarily be turned so as to bring the scale which corresponds to the 115 class of work to be operated upon in position to coöperate with the indicator 38. In the instance shown in Fig. 2, the scale of smallest graduations is shown so positioned. The lever 29 is then moved until the indicator 38 120

points to the graduation which shows the particular size of shoe which is to be buttonholed. In the instance shown in Fig. 2 this is eleven. The movement of the lever 29 rotates the pinion 28 moving the segmental gear 27 which will laterally move the arm 24. For the larger sizes the arm 24 would carry the point of the screw 25 away from the operating point of the machine, while for the smaller sizes the marker 25 is brought nearer to the point of operation. In this way any sort of work may be quickly adjusted, for set and automatically marked.

It will be obvious that various modifications may be made in the construction and operation of my device but these are understood to be included within the spirit of my invention if within the limits of the appended claims.

20 What I therefore claim and desire to secure by Letters Patent is:—

1. The combination with a buttonhole making machine including a work clamp, buttonhole cutting and sewing mechanisms and a moving part independent of the sewing mechanism, of means for designating locations on the work corresponding in position and number to the button-holes to be sewed, said means having actuating connection from the said moving part of the machine for operating the same to make a designation for locating a succeeding button-hole, the parts being arranged to permit movement of the work in a direction from said location designating means to said sewing mechanism between the sewing of successive button-holes and the designating of successive button-hole locations.

2. The combination with a buttonhole making machine including buttonhole cutting mechanism and buttonhole stitching mechanism and a moving part independent of the stitching mechanism, of means for locating designations corresponding in position and number to the button-holes to be produced, said means having provision to locate a succeeding hole and being connected to and operated by the said moving part of the machine as the same is moved in the making of each hole, the parts being arranged to permit movement of successive portions of the work from said location designating means to said hole cutting mechanism between operations.

3. The combination with a buttonhole making machine, having buttonhole cutting and stitching mechanisms for cutting and sewing around a buttonhole, of a marker arranged and located to designate the location of a succeeding buttonhole, means not only to actuate said marker to designate such location of a succeeding buttonhole while the work is positioned for the cutting and stitching of the buttonhole immediately preceding but also to maintain said marker

inoperative while the work is moved into position for the cutting and stitching of the succeeding buttonhole.

4. The combination with a buttonhole making machine, having buttonhole cutting mechanism and stitching mechanism to sew around a buttonhole, of a marker to mark the position of a succeeding buttonhole, automatic means to actuate said marker to mark the location of a succeeding button-hole, including means for maintaining said marker stationary relatively to the work during said buttonhole cutting and stitching operations.

5. The combination with a buttonhole making machine, having stitching mechanism to sew around a buttonhole and a presser-foot movable toward and from the work and constructed and operated to clamp the work continuously during the operation of the stitching mechanism while sewing around a buttonhole, of means for making a mark for a succeeding button-hole as each button-hole is made, said means comprising a marker connected with said presser foot and arranged to be operated once and only once during each cycle of operations of the machine as the presser foot is moved down into clamping position to impress a mark on the work at a predetermined distance from the preceding button-hole.

6. The combination with a buttonhole making machine, including stitching mechanism, buttonhole cutting means, and a movable presserfoot constructed and operated to clamp the work during the operation of buttonhole cutting, of a marker for locating the position of a succeeding button-hole connected to said presser foot so as to impress a mark each time the presser foot moves to clamping position at a predetermined distance from the button-hole being made.

7. A spacer and marker for a button-hole machine comprising a plate having a scale thereon, a marker suitably supported for lateral adjustment relative to the operating point of said machine, a lever arm pivoted to said plate and operatively connected to said marker for causing its lateral movement and a pointer associated with said lever arm for reference to said scale.

8. The combination with buttonhole making mechanism, including means to cut a buttonhole and mechanism to thereafter stitch around the hole so cut and including also a moving part separate from the stitching mechanism, of a device movable toward the work to engage it once during the formation of each buttonhole, said device having thereon a marker for impressing, automatically, a mark at a determinate distance from the hole being made to locate a succeeding hole, said marker being connected for operation by said moving part, and means for adjusting said marker to any one

of a series of precise, predetermined positions relative to the button-hole making mechanism.

9. The combination with a button-hole machine of a vertically operable marker mounted for relative lateral adjustment with regard to the operating point of said machine, means for moving said marker to provide said adjustment, an indicator associated with said moving means, a plurality of scales of different graduations and means for locating any one of said scales in the field of said indicator.

10. The combination with a button-hole machine, having a vertically movable part, of a vertically operable marker pivoted thereon, means for turning said marker to space it with regard to the operating point of said machine, an indicator associated with said turning means and a graduated scale in the field of said indicator.

11. A spacer and marker for a button-hole machine comprising a plate, means for clamping said plate to a vertically movable part of said machine, a marker arm pivoted to said plate, an adjustable marker point on said arm, a scale disk, a lever arm pivoted to said disk and operatively connected to said marker to cause its lateral movement, a pointer on said arm, a scale card rotatably mounted on said disk and having a plurality of marginal scales of different graduations and means for locating any one of said scales in the field of movement of said pointer.

12. A spacer and marker for a button hole machine, comprising a plate, a gage disk adjustable on the plate, a marker arm movably mounted on said plate, a lever arm pivoted centrally of said disk and operatively connected to said marker arm to cause its lateral movement, said disk having a plurality of scales of different graduations, and means for locating any one of said scales in the field of movement of said lever.

13. The combination with a button-hole making machine having means to clamp the work, a buttonhole cutter, and sewing mechanism to sew around a buttonhole so cut, of means automatically operated once during each complete cycle of clamping, cutting and sewing operations of the machine to mark the work for the next succeeding buttonhole at a predetermined distance from the buttonhole being made, whereby the mark may be brought into alinement with the buttonhole cutter in locating the next succeeding buttonhole.

14. The combination with a buttonhole making machine, having a work clamp movable to hold and to release the work and stitching mechanism to sew around a buttonhole while the work is continuously held by said clamp, of a buttonhole marker located at that side of the operating point from which the work is fed while released by said clamp and means automatically operating said marker once but only once during each complete cycle of operations of the machine to designate the location upon the work for the next succeeding buttonhole at a predetermined distance from the button-hole being made.

15. The combination with buttonhole making mechanism, including work clamping, buttonhole cutting and stitching mechanisms of a buttonhole marker automatically actuated by a connection with a movable part of the machine to be operated once during each cycle of operations of the machine to space the next succeeding buttonhole at a distance equal to the distance between the last preceding buttonhole and the button-hole being made, and to remain out of engagement with the work as the latter is moved into position for the cutting and stitching of such succeeding buttonhole.

16. In a buttonhole making machine, the combination with work clamping and buttonhole cutting and sewing mechanisms, including a movable part separate from the sewing mechanism, of a buttonhole marker located at that side of the operating point from which the work is fed and actuated through a connection with said movable part to move into and out of engagement with the work once, but only once, during each complete cycle of operations of the machine in making a buttonhole, said marker being constructed and operated automatically not only to make a mark on the work for the next succeeding buttonhole during said cycle of operations, in which one buttonhole is cut and sewn, but also to remain out of engagement with the work between said cycles of operations while the work is being moved both to carry a sewn buttonhole beyond and to bring said mark to the operating point.

In testimony whereof, I have signed my name to this specification, in the presence of two subscribing witnesses.

ALFRED B. WALES.
